UNITED STATES PATENT OFFICE.

PATRICK J. GAFFY, OF PHILADELPHIA, PENNSYLVANIA.

EXPLOSIVE.

1,399,472.

Specification of Letters Patent. Patented Dec. 6, 1921.

No Drawing.

Application filed April 23, 1920. Serial No. 376,052.

To all whom it may concern:

Be it known that I, PATRICK J. GAFFY, a citizen of the United States, residing at Philadelphia, in the county of Philadelphia and State of Pennsylvania, have invented certain new and useful Improvements in Explosives, of which the following is a specification.

The object of this invention is to provide a highly combustible substance, which is particularly adapted for use by photographers in lieu of the usual flash powder.

Furthermore, this improved material can be so purified that it will form a highly satisfactory substitute for the cotton usually employed as an ingredient in the manufacture of gun-cotton, smokeless powder, nitro-cellulose, celluloid, etc.

Additionally, one of the objects is to make use of the light-weight fiber comprising particularly the head portion of the plant that is quite commonly known as cat-tails, or aquatic weed, and botanically known as *Typha latifolia*, the same recurring perennially in swampy or marshy lands, and obtainable in great quantities with little effort or expense.

Further details of the invention are fully and completely brought out in the following specification, which gives the method whereby all those versed in the art can readily accomplish the desired results.

In carrying out the present invention, the heads of cat-tails are gathered in large quantities and boiled in a solution of common salt ($NaCl$), with a proportion of approximately one-quarter pound of the salt to a quart of water, the latter preferably being previously filtered.

The fiber is then removed from the solution and placed in a suitable press or centrifugal machine to extract as much of the water as possible, and is then completely dehydrated by exposing the same to a slow mild heat, with warm dry air passing over or through the mass in the meanwhile.

After the drying is completely effected, there is added to one pound of the dried previously salined fiber the equivalent of one level table-spoon of nitro-glycerin, great care being taken that the addition of the one ingredient to the other, as well as the subsequent thorough mixing that must be brought about, shall be accomplished at a low temperature in view of the highly explosive nature of the same.

The nitro-glycerin is worked into the fiber until the latter is just moist, after which the resulting compound can be put up in suitable packages, and when ready for use can be placed in or upon a suitable holder, and then ignited in the usual manner, by a flame, hot wire, or spark.

Having thus described my invention, what I claim and desire to protect by Letters Patent of the United States is:—

The method of making an explosive material, the same consisting in boiling cat-tail fiber in a solution of one-quarter pound of salt dissolved in a quart of water, then thoroughly drying said fiber, and mixing with each pound of fiber one tablespoonful of nitro-glycerin.

In testimony whereof I have affixed my signature.

PATRICK J. GAFFY.
